DOOR

Filed Nov. 19, 1923

UNITED STATES PATENT OFFICE.

FRANK W. RADFORD, OF OSHKOSH, WISCONSIN.

DOOR.

Application filed November 19, 1923. Serial No. 675,619.

To all whom it may concern:

Be it known that I, FRANK W. RADFORD, a citizen of the United States, residing at the city of Oshkosh, county of Winnebago, State of Wisconsin, have invented new and useful Improvements in Doors, of which the following is a specification.

This invention relates to an improvement in doors.

10 The invention consists of a door, including stiles and rails, and a panel interposed between and connected to the stiles and rails, and mounted upon each side of the panel and suitably spaced from the stiles and rails is a molding producing a frame or border for the panel.

15 The invention consists of certain novel features of construction and combination of parts which will be hereinafter described 20 and pointed out in the claims.

In the accompanying drawings:

Figure 1 is a view in front elevation of the door;

25 Figure 2 is a detail sectional view in transverse section through a stile, panel and molding;

30 Figure 3 is a detail view in elevation showing the manner of joining the molding strips at the corners; and

35 Figure 4 is a similar view of a modified form of corner strip.

The door is formed of the usual stiles 5, 5, and rails 6, 6, which are recessed or grooved on their inner edge faces, as at 7,

40 Figure 2, for the reception of the edges of the panel 8 which is interposed between the stiles and rails.

45 Superimposed on each side of the panel 8, is a molding, consisting of longitudinal strips of molding 9, 9, and transverse strips 10, 10 suitably spaced, respectively, from the stiles and rails. The ends of the longitudinal strips and transverse strips are joined by means of corner strips 11, 11. The molding strips are fastened to the panel by brads 12 and glue.

50 The several strips of molding have their outer faces uniformly shaped, and are applied to the panel so that they lie adjacent to the stiles and rails, but in spaced relation thereto, for forming a frame for the panel and producing an ornamental design for the door.

In doors such as illustrated in the drawings it is preferred that the molding frame 55 on the panel should conform to the configuration of the framing of the door, but it is not the intention to be restricted to the specific shape or arrangement of the molding as shown.

60 The corner strips 11, are constructed in angular formation, so that the adjoining ends of the corner strips 11, and longitudinal and transverse strips 9 and 10 may be formed with straight edges and not mitered. It has been found that the mitered joint generally employed "opens up," causing a space to be formed between the adjoining ends of the molding strips, and to overcome 65 this objection, the corner strips 11 are provided. By this construction, the ends of the longitudinal and transverse molding strips are joined by the corner strips and to the corner strips by a straight joint, instead of joining the ends of the longitudinal and transverse strips by a miter joint.

70 The corner strips produce and give a neat and finished appearance to the molding frame for the panel and the danger of an "open joint" being formed at the corners of 75 the molding frame, as is the case with the miter joint, is entirely eliminated.

75 In Figure 4, the corner strip 11, is shown rounded, instead of providing a right angular outer corner, as that illustrated in the 80 form of corner strip shown in Figures 1 and 3.

Having described my invention what I claim is:

1. A door, comprising a panel, a series 90 of molding strips mounted on the panel, and corner strips interposed between the adjacent ends of the molding strips and having the ends thereof projecting into the respective paths of the adjoining strips and joined to the ends of said strips.

95 2. A door, comprising a panel, a series of molding strips mounted on the panel, and corner strips interposed between the adjacent ends of the molding strips and having 100 the ends thereof projecting into the respective paths of the adjoining strips and joined to the ends of said strips, the ends of said strips and corner strips being joined by a straight joint.

FRANK W. RADFORD.
